Primary Examiner — Elizabeth J Oswecki(74) *Attorney, Agent, or Firm* — Bartony & Associates, LLC.(57) **CLAIM**

The ornamental design for a visor, as shown and described.

DESCRIPTION

FIG. 1 is a perspective view of a visor showing our new design;

FIG. 2 is a perspective view of the visor of FIG. 1 shown in a used condition connected to a visor frame which is connected to a helmet, wherein the visor frame and helmet are illustrated in broken lines;

FIG. 3 is a front view of the visor of FIG. 1;

FIG. 4 is a rear view of the visor of FIG. 1;

FIG. 5 is a side view of the visor of FIG. 1, the opposite side view is identical;

FIG. 6 is a top view of the visor of FIG. 1; and,

FIG. 7 is a bottom view of the visor of FIG. 1.

The broken lines shown in figures form no part of the claimed design.
